UNITED STATES PATENT OFFICE.

IRA H. SPENCER, OF WEST HARTFORD, CONNECTICUT, ASSIGNOR TO THE SPENCER TURBINE CLEANER COMPANY, OF HARTFORD, CONNECTICUT, A CORPORATION OF CONNECTICUT.

CLEANING-TOOL.

1,162,195.

Specification of Letters Patent. Patented Nov. 30, 1915.

Original application filed December 9, 1909, Serial No. 532,194. Divided and this application filed September 29, 1911. Serial No. 651,953.

To all whom it may concern:

Be it known that I, IRA H. SPENCER, a citizen of the United States, and a resident of West Hartford, in the county of Hartford 5 and State of Connecticut, have invented a new and Improved Cleaning-Tool, of which the following is a specification.

My invention relates generally to the class of devices used for receiving and directing a 10 current of air created by mechanical means, and more especially to that class used in cleaning operations; and an object, among others, of my invention is to provide an improved cleaning tool of extreme simplicity 15 and durability.

One form of device embodying my invention and in the construction and use of which the object above set out, as well as others, may be attained, is illustrated in the accompanying drawings, in which:

Figure 1 is a top plan view of a tool embodying my invention. Fig. 2 is a view in side elevation of the same. Fig. 3 is a detail view on enlarged scale in central lengthwise section through the lower end of the handle showing the method of attachment of the tool to the handle. Fig. 4 is a view in cross-section through the handle on a plane denoted by the dotted line 1—4 of 30 Fig. 3. Fig. 5 is a detail view in lengthwise section through the upper end of the handle showing the means of attachment of a hose connection.

The invention forming the subject matter 35 of this application was originally illustrated and described in my co-pending application for patent for a cleaning tool, filed December 9, 1909, of Serial Number 532,194, this application being a division of said co-pending 40 application.

No specific construction of tool secured to the end of the handle is disclosed herein as such tool may embody different forms of construction so long as the means for securing it to the handle are those forming subject matter of this application.

In the accompanying drawings the numeral 6 denotes the handle of the tool preferably having the curved form shown in 50 the drawings, the outer or tool supporting end 7 being disposed at an angle to and formed of the same piece as that part of the handle from which it projects. A cleaning tool 8 of any desired form and construction

is swivelly mounted on the tool supporting 55 end 7 of the handle, a nipple 9 extending from the back of the tool and preferably being formed integrally therewith.

A clamp sleeve 10 fits over the end 7 of the handle and is secured thereto as by means 60 of interengaging screw threads on said parts, this sleeve serving to removably hold the tool in place. A retaining ring 11 is located between the nipple and sleeve, being located in a groove in one of said parts and engaging 65 a beveled surface on the other part. This ring is a split ring and is of such length that when its ends meet, as shown in Fig. 4, it will not bind the nipple, but will permit free turning movement of the nipple within 70 the ring.

In the preferred form of construction and as shown herein the groove 12 is formed in the nipple, and the beveled clamping surface 13 is formed on the inner surface of the 75 clamp sleeve 10, and a collar 14 is secured to the end 7 of the handle and bears the thread with which the thread on the clamp sleeve engages. The ring 11 will be of such size that it will pass into the space between the 80 inner surface of the sleeve 10 and the outer surface of the nipple 9, and in practice the diameter of the wire composing the ring is a trifle smaller than the width of this space. In any event the ring will be so constructed 85 that it may be passed into the sleeve 10 and located in the groove 12, and when located in said groove may be retained therein by the action of the beveled portion 13 of the sleeve. The clamp sleeve being screwed on 90 to the end of the handle the beveled surface 13 engaging the retaining ring 11 will close its ends together under which conditions the tool 8 will be secured to the handle but will freely swivel thereon.

A stop ring 15, in the form of a split ring, is snapped into a groove 16 at the rear end of the sleeve 10, this stop ring being adapted to engage the collar 14 and serve as a stop to limit the movement of the sleeve in one 100 direction.

The special construction of the joint for attaching the tool to the handle, which enables the tool itself to be removably secured in place and at the same time have free 105 swiveling movement on the handle, is of especial advantage over prior devices in which the tool, while being swivelly united

- to its immediate support, is not removable therefrom. The swiveling of the tool on its support is of advantage only in connection with the tool supporting end of the handle 5 disposed at an angle to the main part, and the removable element therefore becomes of especial advantage in that it simplifies the construction of the handle by lessening the number of parts required in its construction.
- 10 A similar construction is provided at the opposite end of the handle from that supporting the tool, this construction being for the purpose of attachment of a hose connection 17 which has a threaded surface 18 for engagement of the threaded inner surface of a clamp sleeve 19 which may be a duplicate of that hereinbefore described. A stop ring 20, acting in the same manner as that hereinbefore referred to is employed. The beveled 20 inner surface of the collar in this instance acts upon a clamp ring 21 which is split, but the inner ends of which do not meet in the action of the parts. The cross sectional form of this ring as herein shown is angular 25 but other forms may be employed if desired and the ring may be of any suitable fibrous, metallic or other material that will serve to bind the parts. In operation the clamp sleeve 19 is caused to move longitudinally 30 by means of the interengaging threads, and the beveled surface 18 of the collar engaging the split ring closes it upon the handle 6 binding it firmly against the handle and thus securing the parts together. In order 35 to make the ring air tight it is formed as shown in dotted lines in Fig. 5, the ends 22 being shouldered and lapping past each other thus providing an air tight packing, spaces 23 being provided to allow for con- 40 traction of the ring.
- The construction herein shown may be varied to a considerable extent and yet embody the invention, and I do not therefore limit the invention to the exact form of de- 45 vice herein shown and described.
- I claim—
1. A handle having a tool supporting end, a swiveled connection for the handle including a clamp sleeve having a beveled face, 50 and a retaining ring detachably engaging one another to removably secure the tool to the end of the handle without removal of said members and to permit free rotation of the tool upon said tool supporting 55 end.
  2. A handle having a tool supporting end, and a swiveled connection for the handle including a contractible retaining ring, and a clamping sleeve detachably engaged one 60 with the other and attached to the handle to removably secure a tool thereto and to rotate freely thereon, said retaining ring being constructed to loosely engage the tool when securing it in place.
  - 65 3. A handle having a tool supporting end,
- and a swiveled connection for removably securing a tool to the end of the handle to rotate freely thereon, said connection including a retaining ring loosely attached to said tool supporting end, and a clamping sleeve 70 having a beveled face to engage said retaining ring.
4. A handle having a tool supporting end, and a swiveled connection for removably securing a tool to the end of the handle, said 75 connection including a resilient retaining ring engaging a tool to secure it to the tool supporting end and to permit free rotation thereof, and a clamping sleeve having a beveled face to engage said retaining ring 80 to rotatably attach the tool to the handle.
5. A handle having a tool supporting end, and a swiveled connection for removably securing a tool nipple having an annular groove to the end of the handle, said connection including a split ring to hold the nipple, said ring being received in the nipple groove to permit free rotation of the tool 85 and nipple, and a clamping sleeve to engage the ring to rotatably hold the tool to the 90 handle.
6. A handle having a tool supporting end, and a swiveled connection for removably securing a grooved tool nipple to the end of the handle, said connection including a split 95 ring freely surrounding the nipple with its ends arranged to meet, the internal diameter of the ring being slightly greater than the diameter of the nipple groove at the bottom thereof to prevent binding action on 100 the nipple, and a clamping sleeve to engage said retaining ring to rotatably attach the tool to the handle.
7. A handle having a tool supporting end, a swivel connection including a tool provided with a nipple having a groove therein, a retaining ring located in said groove, 105 and a clamping sleeve rotatably mounted on the handle to engage said retaining ring to rotatably attach the tool to the handle.
8. A handle having a threaded tool supporting end, a swivel connection including a clamping sleeve engaging the screw thread upon the end of said handle, a tool provided with a nipple projecting into the handle, said nipple having a groove therein, and a spring retaining ring located within said 115 groove and adapted to be engaged by said clamping sleeve to rotatably attach the tool to the handle.
9. A handle having a tool supporting end with a threaded enlargement thereon forming a shoulder, a clamping sleeve fitting the screw thread upon said enlargement, a tool provided with a nipple projecting into said 125 handle, and a retaining ring secured to the nipple to permit free rotation thereof, said ring being engaged by the sleeve to removably and rotatably attach the tool to the handle.

10. A handle having a tool supporting end, and a swivel connection for removably securing a tool to the handle including a retaining ring, a clamp sleeve engaging said 5 ring to rotatably attach the tool to the handle, and coöperating means carried by the handle and clamp sleeve adapted to prevent disassembling of the sleeve and handle while removing the tool from the handle.

IRA H. SPENCER.
